US0D1048008S

(12) **United States Design Patent** (10) **Patent No.:** **US D1,048,008 S**
(45) **Date of Patent:** **** Oct. 22, 2024**

(54) **SPLIT-SCREEN DISPLAY DEVICE**

(71) Applicant: **Shenzhen E-Tech Digital Technology Co., Ltd.**, Guangdong (CN)

(72) Inventor: **Yang Gu**, Guangdong (CN)

(73) Assignee: **Shenzhen E-Tech Digital Technology Co., Ltd.**, Guangdong (CN)

(**) Term: **15 Years**

(21) Appl. No.: **29/944,401**

(22) Filed: **May 28, 2024**

(30) **Foreign Application Priority Data**

May 8, 2024 (CN) 202430265639.7

(51) **LOC (14) Cl.** **14-02**

(52) **U.S. Cl.** **D14/373**

(58) **Field of Classification Search**

USPC D14/341, 342, 343, 344, 345, 346, 347,
D14/373, 448

CPC ... G06F 1/1647; G06F 1/1652; H04M 1/0268

(57) **CLAIM**

The ornamental design for a split-screen display device as shown and described.

DESCRIPTION

FIG. 1 is a front, right and top perspective view of a split-screen display device in an unfolded position, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2.

FIG. 11 is an enlarged view of detail 11 in FIG. 7.

FIG. 12 is another front, right and top perspective view of the split-screen display device in a position of use; and, FIG. 13 is a perspective view of the split-screen display device, shown in a folded position.

The dashed broken lines depict portions of the split-screen display device that form no part of the claimed design. The dot-dash broken lines in FIGS. 1, 2, 7, and 9-11 depict the boundaries of the enlargements and form no part of the claimed design.

1 Claim, 13 Drawing Sheets
